Fig. 2

This technical drawing illustrates a device assembly, likely a component of a larger machine. The top view shows a rectangular housing (11) with a circular opening on the right side. A handle (28) is attached to the left side. Internal components include a vertical rod (24) with a gear (23) and a lever (47) attached. A cylindrical part (38) is shown in cross-section, featuring a central tube (26) and a piston-like component (39). The side view shows a cylindrical housing (16) with a flared base. Internal parts include a piston (15) and a rod (13). Various reference numerals are used to identify specific parts: 11, 12, 13, 15, 17, 18, 23, 24, 26, 28, 31, 32, 33, 34, 35, 36, 38, 47, 51, 52, 49, and 98.

UNITED STATES PATENT OFFICE

JOHN C. DUNER, OF CHICAGO, ILLINOIS

WATER CLOSET

Application filed January 21, 1931. Serial No. 510,079.

This invention relates to water closets provided for use in railway cars and like locations and while it will hereinafter be described as embodied in a water closet of the general character of that shown in the co-pending applications of John C. Duner for United States Letters Patent, Serial Nos. 375,242 and 375,243, filed July 1, 1929, it will be readily apparent that from certain aspects the invention has broader and more general application.

Toilets of this sort are ordinarily provided with a dump pan adapted to be dumped in flushing with a resultant upflow of air frequently occurring with considerable velocity and producing a blast directed upwardly through the toilet or closet. In the co-pending applications above referred to, a draft member is disclosed for sealing the closet outlet as an incident to the flushing of the toilet. This draft member, preferably and in accordance with the disclosure of said pending applications, moves into a sealing or closing position during the initial opening movement of the dump pan and prior to the breaking of the water seal.

The invention has for its principal object improvement in the dump pan and draft member operating mechanism. The invention contemplates the provision of an operating mechanism of the character described of simple construction, easy operation, and the quick and early closing of the draft member at each flushing of the toilet.

The invention has for a further important object the provision of means for tightly pressing the draft member to sealing position and to hold the same closed with a toggle lock.

Another important object of the invention is the provision of a spring pressed mechanism, the parts of which may be so constructed and arranged as to permit the dumping of the dump pan or its movement to an open position without requiring a corresponding closing movement of the draft member, this feature permitting flushing through the toilet for cleaning purposes in the railway yards.

Numerous other objects and advantages of

the invention will be apparent as it is better understood from the following description, which, taken in connection with the accompanying drawings, discloses a preferred embodiment thereof.

Referring to the drawings:

Figure 1 is a side elevation of a closet embodying the present invention;

Fig. 2 is a front view thereof, parts being broken away and shown in section to disclose certain features of construction;

Figs. 3 and 4 are partial views similar to Fig. 1, showing positions the parts assume in the operation of the closet;

Fig. 5 is an enlarged axial section of the spring housing and associated parts;

Fig. 6 is a detailed sectional view showing the pin and slot connection between the operating arm and the pivot shaft of the dump pan, and

Fig. 7 is a section taken at right angles to the section of Fig. 6.

The water closet shown on the drawings as exemplifying the embodiment of the invention at present preferred, comprises a metal stand or support 11, a ceramic bowl 12 supported by the stand and above the bowl outlet 13, a flush valve mechanism 14, a dump pan 15, and a draft member 16.

The dump pan is pivotally supported in the base for downward swinging, its pivot shaft 17 extending through and being mounted inside bearings 18. At one side, i. e. the side shown in Figs. 1, 3, and 4, the shaft 17 is embraced by a sleeve 19 in which is provided a slot 21. A pin 22 is fixed in the shaft and arranged for movement in the slot 21. An arm 23 is formed integral with the sleeve 19 and is provided at its free end with a pin 24 arranged in a slot 25 in the lower end of a depending link 26 pivotally connected at 27 at its top with a hand lever 28 adapted to be lifted to flush the toilet by dumping of the dump pan and opening of the valve mechanism 14 to provide flushing water.

The draft member 16 is provided with upwardly extending side arms 31 fixed at their upper ends to stud or pivot shafts 32 arranged inside bearings 33. At one side an arm 34 is fixed on the outer

end of the stub shaft 32 and is connected by a link 35 to one arm 36 of a two-armed lever, the other arm 37 of which is connected by link 38 to an end 39 of a reciprocating rod 41 mounted within a sleeve 42 pivoted at 43 on the stand 11. A spring 44 is arranged within the sleeve and bears at its inner end against an enlarged head 45 on the rod 41 and at the other end against a cap 46 arranged about the rod and secured to the open end of the sleeve. The arm 23 is extended beyond its connection with the link 26 into pivotal engagement at 47 with the fulcrum of the lever formed of the two arms 36 and 37.

A weight 48 is arranged upon an extension 49 of the right hand arm 31 (viewing Fig. 2). A second counter balancing weight 51 is provided upon the right hand end of the dump pan pivot shaft 17. The arrangement of the weight 48 and the arms 34 and 31 is such that when the sealing member is in sealing position, i. e. closing the outlet 53 of the closet, the weight 48 has passed vertically beyond the axis 32 of the movement of the draft member to aid in locking the draft member in closed position.

When the hand lever 28 is raised, the arm 23 of the sleeve 19 moves to bring the pin 22 into engagement with the end of the slot 21 and swing the dump pan downwardly. The pin and slot connection just described permit preliminary motion of the draft member to the sealing position shown in Fig. 3 before the dump pan commences its downward swing. Thereafter continued upward movement of the hand lever 28 causes the link 26 to pull up the arm 23, swinging the dump pan down and lifting the weight 51 as may be observed in Fig. 4. During the initial movement, i. e. during the movement while the sealing member is closed, little compression of the spring 44 is accomplished. As the spring is compressed, resulting pressure is exerted to hold the sealing member tightly to its seat.

If desired, the dump pan may be dumped without corresponding closing movement of the draft member by lifting up on the weight 51 to merely swing down the dump pan.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A water closet, comprising a closet bowl supported above its outlet, a dump pan positioned beneath said bowl and adapted to swing from a sealing position downwardly to

a dumping position, a draft member located beneath said dump pan and arrangeable in a sealing position as an incident to the opening movement of said dump pan, and a dump pan and draft member operating mechanism comprising an arm and linkage mechanism connecting said dump pan and draft member and moved over center position into locking relation as the draft member moves to a sealing position. 75

2. A water closet, comprising a closet bowl supported above its outlet, a dump pan positioned beneath said bowl and adapted to swing from a sealing position downwardly to a dumping position, a draft member located beneath said dump pan and arrangeable in a sealing position as an incident to the opening movement of said dump pan, a dump pan and draft member operating mechanism, and a spring pressing said draft member to its seat. 85

3. A water closet, comprising a closet bowl supported above its outlet, a dump pan positioned beneath said bowl and adapted to swing from a sealing position downwardly to a dumping position, a draft member located beneath said dump pan and arrangeable in a sealing position as an incident to the opening movement of said dump pan, and a dump pan and draft member operating mechanism comprising linkage connecting said dump pan and draft member, and spring means engaging said linkage and tensioned to press said draft member to its seat as the dumping occurs. 90

4. A water closet, comprising a closet bowl supported above its outlet, a dump pan positioned beneath said bowl and adapted to swing from a sealing position downwardly to a dumping position, a draft member located beneath said dump pan and arrangeable in a sealing position as an incident to the opening movement of said dump pan, and a dump pan and draft member operating mechanism comprising arms arranged for pivotal movement respectively with said dump pan and said draft member, a plurality of successively connecting links connecting said arms, and spring means for pressing said draft member to its seat during dumping. 100

5. A water closet, comprising a closet bowl supported above its outlet, a dump pan positioned beneath said bowl and adapted to swing from a sealing position downwardly to a dumping position, a draft member located beneath said dump pan and arrangeable in a sealing position as an incident to the opening movement of said dump pan, and a dump pan and draft member operating mechanism comprising arms connected respectively to said dump pan and said draft member, spring means resisting dumping in the conjoint opening movement of the dump pan and closing movement of the draft member, and means for moving the dump pan to dumping 115 120 125 130 135

position independently of movement of said draft member.

6. A water closet, comprising a closet bowl supported above its outlet, a dump pan for closing the outlet of said closet bowl, a draft member movable to a sealing position beneath said dump pan, a linkage between said dump pan and said draft member and moving said draft member to a fully closed position prior to the initial opening movement of said dump pan.

JOHN C. DUNER.
